Alphon Kirner

UNITED STATES PATENT OFFICE.

ANTON KIRNER, OF NEUSTADT, GERMANY.

MOTION-RECORDING APPARATUS.

Application filed March 24, 1927, Serial No. 173,115, and in Germany May 2, 1925.

This invention has reference to improvements in controlling and recording devices as applied to the recording of movements particularly in the case of vehicles of that kind in which a pendulum member to which a reciprocating oscillating movement is imparted by the occurring vibrations is utilized for the purpose of actuating a recording member, stylus, pencil or the like. Among 10 other features, my invention comprises an important improvement in the devices above referred to in so arranging and constructing the lever or the like on which the stylus is mounted, that the lever may be connected to 15 the pendulum member by means of a friction coupling the friction of which, though being in excess of that of the moving recording stylus or the like, on the other hand is insufficient of preventing the pendulum member 20 from returning to its vertical position by its own weight in the case of an excessive inclination of the vehicle. Such a kind of yielding connection between the pendulum member and the recording means produces 25 the advantage moreover that a stop may be provided for the purpose of limiting the movement of the recording member without any danger of producing injury to the apparatus in the case of unduly large amplitudes 30 of the pendulum member.

When employing a rotatable registering disc for recording purposes it is possible to constantly change or vary the relative position of the stop and consequently the position 35 of the recording member, stylus or the like in regard to the mechanical transmitting means, such as a gear wheel and a segmental lever by means of a clockwork, so as to impart a substantially spiral configuration 40 to the recording line so that one and the same recording disc will retain its usable condition for a comparatively long time, for several days, for instance, without the necessity of being exchanged for a fresh one.

45 The invention will be more fully described by reference to the accompanying drawing showing by way of exemplification an illustrative embodiment of the principles of the invention in Figure 1 in front elevation; Figure 2 is a sectional view on the line A—B of Figure 1; Figure 3 is a sectional view on the line C—D of Figure 1 and Figure 4 is 50 a view of the internal construction of a controlling apparatus adapted for relatively longer operation. Figure 5 is a section on

the line E—F, Figure 4 with the cover shown in side view.

The rod 1^a of the pendulum 1, as shown in Figures 1 to 3, is rotatably mounted on the bearing collar 3 of the lever 5 which is 60 rigidly connected to the rocking shaft 2. The friction coupling or clutch between the parts 1^a and 5 in the exemplification shown comprises a spiral spring 4 adapted to force the neck of the pendulum rod 1^a against the 65 enlarged, flange-like middle portion of the double-armed lever 5, while the other end of the spring is adapted to bear on the marginal portion of a stopping collar 8 secured to the shaft 2. The shaft 2 is disposed between the rear wall of the casing 6 and a bearing member 7 secured to the front wall of the casing, the shaft 2 being thereby free 70 to be readily oscillated. The lever 5 which is coupled to the pendulum 1 by the frictional clutch referred to is provided with two oppositely directed lever arms 5^a and 5^b of which 5^a carries the stylus 10, while the lever arm 5^b carries a stud 11 engageable 75 with a guiding and confining slot 12 in the rear wall of the casing 6. In the operation of the apparatus a registering surface 10^a is moved past the recording stylus 10, thus for instance by means of clockwork mounted 80 in the box 9.

85 The device operates substantially in the following manner. As a result of the vibrations of the vehicle during operation or even in the inoperative position thereof and while the engine is moving the pendulum 1, 1^a is 90 caused to oscillate and as result thereof the vibrations will be recorded on the writing surface 10^a by the operation of the recording member 10 and in view of the frictional coupling between the members 1^a and 5. The 95 movement of the stylus or recording member 10 is confined by the path of the stud 11 in the recess 12 of the rear wall of the casing 6. The friction at the clutch between the members 1^a and 5 is larger than the operating friction between the recording surface 10^a and the stylus 10, but it is so adjusted that the pendulum member 1, 1^a is 100 adapted to re-assume its vertical position by overcoming the frictional resistance at the clutch between the parts 1^a and 5, thus for instance in case the vehicle is in the inclined position, so that the pendulum will 105 remain operative.

110 In the exemplification shown in Figures

2

4 and 5 of the drawing the controlling apparatus is provided with a recording surface 10^a serving as a registering disc. In this embodiment the recording stylus 10 per-
 5 forms a spiral-like path, so as to be able to utilize the registering surface for a com-
 paratively long time of operation. The clockwork for driving the said registering or recording disc, and which is not shown
 10 in the drawing, is mounted preferably in the cover 13 of the casing which is prefer-
 ably connected by link connection 15 to the bottom portion 6 of the casing, so as to al-
 low of swinging the cover into the open
 15 position and to return the cover into the closing position. The extension of the driving shaft 16 of the clockwork or of the reg-
 20 istering or recording disc 10^a constitutes a gear member 16^a which, in the closing posi-
 25 tion of the casing sections 6 and 13 is adapt-
 ed to become engaged with a gear segment 17 the carrying arm 14 of which is mounted
 30 on a bearing stud 18 suitably disposed in the casing section 6, so as to allow of a ro-
 35 tation of the arm 14. At its rotating point
 40 the bearing arm 14 of the segmental gear 17 is rigidly connected to a lateral projection
 45 provided with a substantially forked ex-
 tremity adapted to embrace the guide pin
 50 11 at the lever end 5^b. The pendulum 1,
 55 similar to the exemplification shown in Fig-
 60 ures 1 to 3, is adapted to be connected by
 65 frictional clutch and by the action of a
 70 spiral spring 4 to the lever 5 in such a man-
 75 ner that the pendulum is always adapted to
 80 assume its vertical position by overcoming
 85 the coupling friction. Thus for instance, if
 90 the clockwork mounted in the cover or lid
 95 13 of the casing and arranged for a run-
 100 ning period of, say one week is slowly run-
 105 ning off the driving pinion 16^a which is op-
 eratively connected to the driving shaft of
 110 the clockwork and to the registering disc
 10^a will rotate the segmental lever 17, 14, 19
 115 on its pivoting point 18, which results in
 120 the change of position of the lever 5 and of
 125 the recording stylus 10 disposed on the lever
 130 end 5^a by the intermission of the parts 19
 135 and 11, so as to slowly alter its position with
 140 relation to the center of the rotatable reg-
 145 istering or recording disc 10^a. By this means
 150 a substantially spiral-like recording line is
 155 obtained, so that the rotating registering or recording surface 10^a may be utilized

much more completely, thus for instance for 55
 a running time of an entire week, and with-
 out the necessity of being exchanged.

Upon the swinging open of the casing the driving wheel 16^a becomes disengaged from the segment 17, so that this segmental gear 60
 17 and the lever 5 controlled thereby with the recording stylus 10 may be restored to the initial position at the upper edge of a
 65 freshly inserted registering or recording sheet 10^a.

The toothed segment 17 is preferably suf-
 70 ficiently resilient or arranged in such a manner that upon the impinging of two teeth of the parts 16^a and 17 upon each other likely to occur upon the sudden closing of 75
 the casing the easy and not forcible en-
 gagement of these operating parts becomes possible.

It should be understood that the invention 75
 has been shown herein in its broad aspects
 only, and that it is susceptible of changes
 and modifications other than those herein
 described and illustrated by way of exem-
 plification and without thereby deviating
 80 from the spirit and scope of the invention,
 as set forth in the appended claims.

I claim:—

1. In a motion recording apparatus in combination, supporting means, an oscillatable pendulum-body rockingly disposed on 85
 90 said supporting means, a two-armed lever in frictional engagement with said pendulum-body, recording means on one of the arms of said lever, and guiding and adjusting means on the other lever arm, a movable recording surface in sliding contact with the recording means and producing less friction than the frictional engagement of the lever.

2. In a motion recording apparatus in 95
 combination, supporting means, an oscillatable pendulum-body rockingly disposed on
 100 said supporting means, a movable recording surface, recording means in contact with said surface, and a frictional coupling, slid-
 105 ingly connecting the recording means to the pendulum body and adapted to overcome the friction on the recording surface, a cam member engageable with the recording means, and means on the recording surface, operatively engaging said cam member.

In testimony whereof I affix my signature.
 ANTON KIRNER.
